Fig. 4

Fig. 5

Fig. 6

Fig. 7

Fig. 8

FIG. 1 is a perspective view of a travel kit embodying my new design, shown in open position.

FIG. 2 is a top plan view of the travel kit in open position.

FIG. 3 is a side elevational view of the travel kit, in open position.

FIG. 4 is a top plan view of the travel kit, closed.

FIG. 5 is a front elevational view of the travel kit, closed.

FIG. 6 is a side elevational view thereof, the side opposite being reversely similar.

FIG. 7 is a bottom plan view of the travel kit, closed.

FIG. 8 is a rear elevational view of the travel kit, closed.

I claim:

The ornamental design for a travel kit, as shown and described.
